UNITED STATES PATENT OFFICE.

LEON F. BAUMANN, OF FITZDALE, VERMONT.

ATTACHMENT FOR BAG-MAKING MACHINES.

1,400,404.

Specification of Letters Patent. Patented Dec. 13, 1921.

Application filed November 23, 1920. Serial No. 425,999.

To all whom it may concern:

Be it known that I, LEON F. BAUMANN, a citizen of the United States, residing at Fitzdale in the county of Essex and State 5 of Vermont, have invented new and useful Improvements in Attachments for Bag-Making-Machines, of which the following is a specification.

This invention relates generally to machines wherein use is made of a paste roller for supplying the product of the machine with paste for an adhesive substance, the invention being shown and described in connection with the bag-making machine, although its general application is contemplated by the claims.

In a machine of this character the paste roller operates within a container for paste or other adhesive substances, and a considerable portion of the paste taken up by the roll is thrown therefrom incident to centrifugal force. This results in the waste of the adhesive substance, clogging of the working portions of the machine and a decrease in production.

It is therefore the purpose of this invention to provide a means to overcome these objections, by collecting the substance thrown from the paste roll in the manner 30 above described, and returning it to the container for the same.

To this end use is made of a roll arranged in juxtaposition to the paste roll to catch the substance thrown from the latter incident to centrifugal force, with means for scraping the said roll and returning the surplus paste or adhesive substance to the container therefor, thereby eliminating waste, as well as permitting the machine a 40 higher rate of speed with an increase of production.

The nature and advantages of this invention will be better understood when the following detail description is read in connection with accompanying drawings which 45 form part of this application.

In the drawings forming part of this application like numerals of reference indicate the similar parts in the several views 50 and wherein:—

Figure 1 is a side elevation of a machine with which the attachment is used, showing the attachment in position for use.

Fig. 2 is a fragmentary sectional view 55 therethrough.

Fig. 3 is a view of the adjustable bearing for one of the rolls.

Fig. 4 is a perspective view of the scraper.

Referring to the drawings in detail A indicates generally a paper bag-making machine wherein 10 represents the container for the paste or adhesive substance. What I term a paste roll is indicated at 11, this roll partly projecting within the container 10 and operating to transfer the paste or adhesive substance from the container 10 to the paste knife 12 of the machine. This is an old and well known construction, and it has been found that a considerable quantity of the paste or the like taken from the 70 container 10 by the roll 11 is thrown from the container by centrifugal force which results, not only in fouling the working parts of the machine with a consequent reduction in efficiency, but also results in the waste 75 of this surplus paste.

The present invention embodies a roll 13 disposed in juxtaposition to the paste roll 11 to collect the surplus paste thrown from the roll 11 incident to centrifugal force. 80 The roll 13 is preferably arranged immediately above and slightly in advance of the paste roll 11, occupying a position so that the paste thrown from the roll 11 will strike the roll 13. A belt 14 is utilized to rotate 85 the roll 13 in a direction away from the roll 11 although any other suitable means may be employed for this purpose. Projecting from a fixed part of the machine is a scraper 15 curved over the roll 13 and terminating to provide a flange 16 which bears against the periphery of the roll 13, so that as the latter is rotated, the paste or adhesive substance taken by the roll 13 is removed therefrom and allowed to gravitate back 95 into the container 10.

While it is believed from the foregoing description the nature and advantages of the invention will be readily apparent, I desire to have it understood that I do not 100 limit myself to what is herein shown and described, and that such changes may be resorted to as fall within the scope of what is claimed.

What I claim is:—

1. In a machine of the class described the combination with a paste roll, of an additional roll arranged in juxtaposition to the paste roll to collect the paste thrown therefrom by centrifugal force, means for ro-

tating the latter mentioned roll and a scraper for said roll.

2. In a machine of the class described, the combination with a paste container and 5 a paste roll operated within the latter, of an additional roll arranged adjacent the paste roll to receive the paste thrown from the latter by centrifugal force, means for

rotating said additional roll, a scraper including a member curved over said additional roll and having one end bearing against the latter to remove the paste therefrom, said scraper being designed to direct the said paste into said container. 10

In testimony whereof I affix my signature. 15

LEON F. BAUMANN.
